UNITED STATES PATENT OFFICE.

EDWARD HETT, OF NEW YORK, N. Y.

MACHINE FOR MAKING PRINTING-SURFACES.

SPECIFICATION forming part of Letters Patent No. 637,597, dated November 21, 1899.

Application filed January 5, 1899. Serial No. 701,192. (No model.)

To all whom it may concern:

Be it known that I, EDWARD HETT, a citizen of the United States, and a resident of New York, (New Dorp,) in the county of Richmond, 5 State of New York, have invented new and useful Improvements in Mechanism for Making Printing-Surfaces, of which the following is a specification.

This invention relates to a machine adapted 10 for use in making printing-surfaces, whether planographic, relief, intaglio, or other printing surface.

The object of the invention is to provide a machine whereby printing-surfaces may be 15 accurately and economically made in accordance with my new process, as set forth in an application filed by me on October 4, 1899, Serial No. 723,439.

The machine embodying the present invention is organized to bring into coöperation a 20 primary surface—*i. e.*, a surface developed and capable of printing—a permanent conveying-surface adapted to effaceably receive an imprint of the design of the primary surface, and a secondary surface—*i. e.*, a surface adapted to be made into a printing-surface. These three surfaces are arranged and 25 designed to coöperate in such a way that the primary surface prints its design upon the 30 conveying-surface and the conveying-surface imparts the same design upon the secondary surface. The secondary surface is then developed and becomes a printing-surface or the “secondary printing-surface,” as the secondary surface when developed will be herein 35 called.

In the practical use of the invention a plurality of designs is imposed upon the primary printing-surface in accurate predetermined 40 mutual relation with reference to the printing of those designs by the secondary printing-surface in accurate predetermined positions on the impression-surface and with reference to register. This plurality of designs is generally imposed upon the primary surface by sticking up a plurality of ordinary transfers 45 upon a setting-up plate in accurate predetermined mutual relation which they are to have upon the secondary surface. These transfers 50 are then turned over upon the primary surface, which is thereupon developed, so as to be capable of printing. The secondary sur-

face has imparted to it from the primary surface this plurality of designs in the same identical mutual relation. To accomplish this result, I impart the designs of the primary printing-surface to the conveying-surface, which is then imparted to the secondary surface. Thus it will be seen the secondary surface has imparted to it a plurality of designs in 60 accurate predetermined mutual relation and from a unitary surface bearing said designs in the same identical relation, the conveying-surface being a unitary basic surface with respect to the secondary surface. 65

The invention consists of the features and combinations of features herein set forth.

In the drawings showing one embodiment of the invention and forming part of this specification and in which like reference-numbers designate corresponding parts, Figure 1 is a side elevation of a machine embodying the invention, looking in the direction of the arrow 1, Fig. 5. Fig. 2 is a side elevation looking toward the opposite side of the machine. Fig. 3 is a vertical sectional elevation on the line 3 3, Fig. 4. Fig. 4 is a plan view, and Fig. 5 is an end elevation. Fig. 6 is a sectional elevation of the primary surface seated on its support. 75

Referring now more particularly to the specific structure of the machine embodying the invention as shown in the drawings, 1 is a surface prepared or developed, so as to be suitable for printing and for convenience herein called the “primary surface.” In its preferred form it is curved or cylindrical and shell-like, as shown, is a continuous cylindrical tube, and is mounted on a support 2, carried on the shaft 3, which is mounted in 90 boxes 4, supported by the frame of the machine. The primary surface is removable from the machine, and for this purpose the shaft 3, with the printing-surface and its support, may be removed, or, as is preferred, the 95 printing-surface may be removed from its support. Both arrangements are shown in the drawings. The primary surface 1 has an accurate pre-established seat in the machine, so that it and successive primary surfaces may 100 be mounted therein in accurate predetermined position both longitudinally and transversely. The seat for the primary surfaces is on the rotary support 2. The ribs 5,

formed on the inner side of the primary surface, and the corresponding longitudinal grooves formed on the support 2, in which the ribs fit, a marked rib in a marked groove, determine the transverse or circumferential location of the primary surface in its seat. The longitudinal position of the primary surface on its support is determined by the collar or stop 102, formed on one end of the support 2, (see Fig. 6,) against which the primary surface accurately fits when mounted in its seat on the support. The arrangement of the primary surface and its support as shown in Fig. 6 is substantially the same as that of the printing-form shown and described in my pending application, Serial No. 537,582, filed February 7, 1895. Thus pre-established guides for quickly and accurately seating the primary surface are provided. Of course various other forms of pre-established guides for seating the primary surfaces may be employed. The boxes 4 are mounted in horizontal recesses 6, in which they may slide. The extensions 7 of the frame are in line with the recesses 6, and one of said extensions is movable up and down by the screw 8, which extends through the collar 9 on the main frame and through the threaded hub of the hand-wheel 100, resting on said collar. By turning the hand-wheel the screw moves vertically up or down through the collar, and so moves the extension. When the boxes 4 are moved back upon the extensions 7, that end of the shaft 3 supported by the movable extension 7 may be supported by outside means and the movable extension 7 may be then lowered and the printing-surface 1 slipped from its support, or, if desired, the shaft and all may be removed.

10 is the secondary surface, adapted to be made into a printing-surface, and when so made it becomes the secondary printing-surface. It is mounted on a support 11, carried by the shaft 12, which is supported in boxes 13. The secondary surface is similar in arrangement to the primary surface. It has an accurate pre-established seat on the support 11, in which it and successive secondary surfaces may be mounted in accurate predetermined position both longitudinally and transversely and with reference to pre-established guides, these guides being the same as those shown and described for the primary surface. It is likewise removable, for which purpose there are provided the extensions 14, one of which is movable, and the screw 15. The boxes 13 are movable in the recesses 16. The primary surface is designed in accordance with this invention to print—*i. e.*, impart the ink of the design or the plurality of designs carried thereby to a conveying-surface, which then by being made to contact with the secondary surface imparts to the secondary surface the impression it has received. This conveying-surface may be flat or curved or cylindrical in form and preferably consists of some material suitable to effaceably receive

an impression from the primary surface and adapted to remain permanently in place during repeated or successive operations.

70

17 is the conveying-surface, herein shown as curved and secured to and carried by the cylindrical support 18, mounted on the shaft 19. The surface 17 is preferably a sheet or blank of rubber stretched over its support 75 and may be secured to rods 20, or it may be a sheet of some other suitable material which will admit of having the impressions imparted to it from the primary surface being effaced, so that it may be repeatedly used and so permanently remain in the machine.

80

In order that the conveying-surface may have contact with the primary surface and with the secondary surface, the primary and secondary surfaces are made movable to and from the conveying-surface. This is accomplished by moving the boxes 4 and 13 in their recesses. Various means may be employed for moving the boxes; but in the present instance I employ for the boxes 4 levers 21, pivoted to the frame on either side and which carry the arms 22, pivoted thereto and provided with hooks 23, which engage the ends of the shaft 3. To positively hold the hooks in engagement with the shaft 3, I may provide the hooks 23 with projections 24, adapted to move under flanges 25, fixed on the main frame.

95

26 are handles on the hooks 23 for lifting them.

100

27 is a hand-lever pivoted on the frame and provided with segmental gear 28, meshing with the gear 29, fixed on the shaft 30, carried by the frame. On the shaft 30 are fixed eccentrics 31, which rotate in elliptical ways 32, 105 formed on the ends of the levers 21. By operating the hand-levers 27 the cylinder 2 is moved back and forth, so as to bring the primary surface 1 into firm contact with the conveying-surface when desired and so as to move the cylinder 2 into position for the removal of the primary surface. The lever 27 has a bolt 33, arranged to engage a segment 34 on the frame, so as to lock the cylinder 2 in the position desired. It is important that 110 the conveying-surface 17 work in positive contact with the co-operating primary or secondary surfaces, so that neither may slip on the other, and for this purpose the conveying-surface has a gear-wheel 35 fixed on the shaft 19. It meshes with the gear-wheel 36, fixed on the shaft 3, so that the conveying-surface and primary surface work in positive contact. These gear-wheels are so marked that they may always be meshed in identically the same 115 way in order that the primary surface and conveying-surface may be brought into an accurate predetermined co-operating relation and the impression of a primary surface may always be imparted to the conveying-surface 120 in the accurate predetermined position.

125

38 is a frame carrying dampening-rollers for the primary surface and moved to and from the primary surface by the shaft 39, hav-

130

ing eccentrics 40 rotating in the elliptical openings 41, formed in the frame 38. The shaft 39 is operated by a hand-wheel 42 on the shaft, and the frame 38 is guided by ribs 43, formed on the inner sides of the frame.

44 is the inking-frame carrying inking-rollers for the primary surface, of which inking-rollers 45 is the main ink-distributing cylinder, carried on the shaft 46, by which the inking-rollers are driven through suitable gearing. The inking-frame 44 has offsets 47, in which are journaled the shaft 46 and which are movable up and down in the recess 48 in the frame, whereby the frame 44 and its rollers may be moved to and from the primary surface. Fixed on the frame 44 are screws 49, passing through caps 50, fixed on the frame above the recesses 48. Threaded on the screws 49 and within openings in the caps 50 are gears 51, meshing with gears 52, fixed on the shaft 53. A hand-shaft 54, carrying a gear 55, meshing with a gear 56, fixed on the shaft 54, operates to rotate the shaft 54, and thereby the gears 52, which, as they are held in their seats while turning in the caps 50, lift or lower the screws 49, thus moving the frame 44 so as to bring the inking-rollers into and out of contact with the primary surface as desired.

The secondary surface 10 is equipped with devices operating and arranged in the same way as those just described for the primary surface. These devices are all clearly shown in the drawings and need not therefore be described. I will only designate some of them by reference-numerals. There is the gear 89, fixed on the shaft 12, carrying the cylinder 11 and having a marked tooth to mesh with a marked recess in the gear 35, whereby the conveying-surface and secondary surface 40 may be brought into accurate predetermined relation, the hand-lever 57 for moving the cylinder 11 to and from the cylinder 3, the dampening-frame 58, operated by the hand-shaft 59, the inking-frame 60, whose inking-rollers are driven from the main ink-distributing cylinder 61, carried on the shaft 62, and the hand-shaft 63 for moving the inking-frame.

I will now describe the mechanism whereby the printing-surfaces are separately driven each with its inking-rollers and whereby these surfaces are separately driven in contact with the conveying-surfaces.

64 is the main driving-shaft, on which are mounted the sleeve 65, carrying the gears 66 and 67, and the sleeve 68, carrying the gears 69 and 70. The sleeves 65 and 68 are made fast on the shaft 64 by means of the clutch 71, operated by a lever 72, which is actuated by the shaft 73, having the eccentric 74 and the segmental gear 75. This gear 75 is operated by a hand-shaft 76. The sleeves 65 and 68 serve to drive separately the printing-surfaces, with their ink-rollers, and also the printing-surfaces, with the conveying-surface. The gear 70 of the sleeve 68 meshes with the gear 77, fixed on the shaft 78, which carries

the gear 79, meshing with the gear 80, fixed on the shaft 46 of the cylinder 45. The gear 79 is carried by a bracket 81, carried by the bracket 101, fixed to the inking-frame 44, and is moved lengthwise on the shaft 78 when the frame 44 is moved, the gear 79 being secured on the shaft by the feather 82. Thus the inking-rollers may be rotated by themselves apart from the primary surface. The gear 69 of the sleeve 68 meshes with the gear 83, fixed on the shaft 84, which carries the gear 85, meshing with the gear 86, fixed on the shaft 3 of the cylinder 2. The gear 85 is carried by a bracket 87, fixed on one of the boxes 4 of the shaft 3, and is moved lengthwise on the shaft 84 when the boxes are moved, being secured on the shaft by the feather 88. Thus the primary surface may be driven when in contact with the inking-rollers or when in contact with the conveying-surface.

The gearing for the secondary surface and its inking-rollers is identical with that for the primary surface and need not be specially described. The cylinder 18 of the conveying-surface, it will be seen, is driven through the gear 36, which is fixed on the shaft 3, and meshes, as already described, with the gear 35, fixed on the shaft 19. In the same way when the conveying-surface is in contact with the secondary surface the gear 35 meshes with a gear 89, fixed on the shaft 12, the gears 35 and 89 being marked so as always to mesh in the same way.

In the operation of the machine the primary surface 1 having been suitably inked is brought into contact with the conveying-surface 17 by operating the lever 27. The clutch 71 having been operated to lock the sleeve 68 on the shaft 64 the shaft 64 is then driven. The shaft 64 thereupon through the gears 69, 83, 85, and 86 drive the shaft 3, carrying the primary surface and its gear 36. Thus the gears 36 and 35 being in mesh cause the primary surface and the conveying-surface to rotate together in positive contact, thereby imparting the design of the primary surface to the conveying-surface. The primary surface is then separated from the conveying-surface by again operating the lever 27, and the lever 57 is operated to bring the secondary surface into contact with the conveying-surface and the gears 35 and 89 into mesh. The clutch 71 is reversed, so as to lock the sleeve 65 upon the shaft 64 and unlock the sleeve 68 from said shaft. The shaft 64 is then driven, which, through the gear 66 and connecting-gearing, drives the shaft 12, carrying the secondary surface and the gear 89. Thus the secondary surface and the conveying-surface are positively rotated together in contact, so that the design of the conveying-surface is imparted to the secondary surface. The secondary surface is then separated from the conveying-surface by operating the lever 57, the hand-shaft 63 is turned to lower the inking-frame 60, and the shaft 59 is turned to raise the dampening-frame 58. The secondary

surface is then developed. In this operation the secondary surface and inking-rollers are positively driven from the driving-shaft 64, for this purpose the sleeve 65 still remaining 5 locked on the shaft. The secondary surface having been thus made is thereafter removed from the machine and may be then mounted in the press and employed in printing.

Of course, if desired, the secondary surface 10 may be removed from the machine and subsequently developed, the inking and dampening frames being dispensed with. In removing and mounting a primary or secondary surface from the machine I may employ apparatus such as is shown in an application filed 15 by me on July 12, 1898, Serial No. 685,764. In removing the secondary surface the lever 57 is operated to move the boxes 13 upon the extensions 14 of the frame. If desired, the 20 shaft 12, with the supporting-cylinder 11 and the secondary printing-surface, may then be removed and mounted in the printing-press. I prefer, however, to remove the printing-surface 10 from its supporting-cylinder 11. 25 In doing this convenient means—such as the apparatus described in my pending application, Serial No. 685,764, above referred to—is made to support one end of the shaft 12. The screw 15 is then operated to lower the extension 14, so as to clear the printing-surface 10, and the printing-surface is slipped from its supporting-cylinder. The second printing-surface may be then mounted upon the cylinder 11 by employing the means described 30 for the removal of the secondary surface or secondary printing-surface 10. In the same way the primary surface may be removed and a new one mounted in the machine. The same primary surface may be used in making 35 a plurality of identical secondary surfaces successively supported in place in the machine in the same definite and predetermined position, whereby the designs on such plurality of secondary printing-surfaces will 40 be identical and identically placed thereon, and these secondary printing-surfaces may be and preferably are interchangeable with one another and with their coating primary surface and constructed and designed to fit 45 50 in a pre-established seat or seats in a printing-press. A series of primary surfaces designed and constructed for register may be successively supported in definite and predetermined position in the machine and each 55 employed in making a plurality of identical secondary printing-surfaces, so that from the series of registering primary surfaces a plurality of series of registering secondary printing-surfaces may be made. The supporting- 60 cylinders 2 and 11 are preferably identical, as shown, and it is evident that instead of supporting the primary and secondary surfaces on separate cylinders the primary surface after printing on the conveying-surface 65 may be removed and a secondary surface substituted therefor on the same cylinder and be brought into coaction with the conveying-

surface having the design of the primary surface printed thereon. In this way the secondary printing-surface may be made identical 70 with the primary surface with the same accuracy as where the primary and secondary surfaces are supported on their different cylinders. It will be seen that when the primary and secondary surfaces are supported 75 on the same cylinder they are arranged in the same definite and predetermined co-operating relation with respect to each other and also with respect to the conveying-surfaces. Where they are supported on the separate 80 cylinders, they are supported in equivalent definite and predetermined co-operating relation with respect to each other and with respect to the conveying-surface. The successive primary surfaces are arranged in the 85 same position and in the same relation with respect to the support for the conveying-surface or with respect to the successive conveying-surfaces carried thereby. The same is true in regard to the successive secondary 90 surfaces. The successive coacting primary and secondary surfaces are, moreover, arranged in the same relation with respect to each other.

It will be noted that this invention makes 95 it possible to dispense with the employment of a separate setting-up plate, heretofore required in making each printing-surface, and that great economy is effected in time and labor and painstaking care, heretofore required in making printing-surfaces, especially printing-surfaces designed to register, as in multicolor-printing, wherein as many as ten to twenty registering printing-surfaces are sometimes used in a job. Of course mechanism employed for operating and handling the primary surface, secondary surface, conveying-surface, and inking and dampening devices may be used in connection with any character of conveying-surface and whether 105 permanent or not. For example, a sheet of paper, removed after each operation, may be used as the conveying-surface.

The primary and secondary surfaces may be made of any suitable material, but are 110 preferably made of metal which may be electrolytically deposited upon a suitable base. I prefer to electrolytically deposit zinc upon copper. In developing the primary and secondary surfaces any suitable method may be 115 used—such as light or deep etching, routing out, &c.—and they may be developed so as to be planographic, relief, intaglio, or otherwise. The primary and secondary surfaces may be differently or similarly developed. 125

While it is of course important that the rolling contact of the conveying-surface with the primary and secondary surfaces be positive—that is, without slipping—it is not essential that intermeshing gears be employed 130 for this purpose. Other means may be employed to accomplish the result and to drive the bodies in unison, and intermeshing gears may be dispensed with. Again, while I make

use of a marked tooth and a marked recess in the intermeshing gears as preëstablished guides to bring the primary surface and conveying-surface and the secondary surface and conveying-surface into accurate predetermined coöperating relation it will be obvious that various other devices may be used for this purpose.

Various changes may be made in the mechanism herein shown and described for operating the primary, secondary, and conveying surfaces, and various changes may be made in the shape and arrangement of the primary, secondary, and conveying surfaces, and various features may be employed apart from other features and in different relations.

What I claim as new, and desire to secure by Letters Patent, is—

1. In a machine designed to be used in making printing-surfaces, the combination of a primary printing-surface adapted to print a design; a secondary surface adapted and arranged to receive an impression by contact and to be developed into a printing-surface; a permanent conveying-surface arranged and adapted to effaceably receive an impression from the primary surface and to impart it to the secondary surface; preëstablished guides with reference to which the primary and secondary surfaces may be arranged in a precise predetermined coöperating relation both longitudinally and transversely with respect to the conveying-surface, whereby the design of the primary surface may be imparted to the secondary surface in a precise predetermined position.

2. In a machine designed to be used in making curved or cylindrical printing-surfaces, the combination of a primary printing-surface adapted to print a design; a curved or cylindrical secondary surface adapted and arranged to receive an impression by contact and to be developed into a printing-surface; a permanent conveying-surface arranged and adapted to effaceably receive an impression from the primary surface and to impart it to the secondary surface; preëstablished guides with reference to which the primary and secondary surfaces may be arranged in a precise predetermined coöperating relation both longitudinally and transversely with respect to the conveying-surface, whereby the design of the primary surface may be imparted to the secondary surface in a precise predetermined manner.

3. In a machine designed to be used in making lithographic printing-surfaces, the combination of a primary printing-surface adapted to print a design; a lithographic secondary surface adapted and arranged to receive an impression by contact and to be developed into a printing-surface; a permanent conveying-surface arranged and adapted to effaceably receive an impression from the primary surface and to impart it to the secondary surface; preëstablished guides with reference to which the primary and secondary surfaces

may be arranged in a precise predetermined coöperating relation both longitudinally and transversely with respect to the conveying-surface, whereby the design of the primary surface may be imparted to the secondary surface in a precise predetermined position.

4. In a machine designed to be used in making curved or cylindrical lithographic printing-surfaces, the combination of a primary printing-surface adapted to print a design; a curved or cylindrical lithographic secondary surface adapted and arranged to receive an impression by contact and to be developed into a printing-surface; a permanent conveying-surface arranged and adapted to effaceably receive an impression from the primary surface and to impart it to the secondary surface; preëstablished guides with reference to which the primary and secondary surfaces may be arranged in a precise predetermined coöperating relation both longitudinally and transversely with respect to the conveying-surface, whereby the design of the primary surface may be imparted to the secondary surface in a precise predetermined position.

5. In a machine designed to be used in making curved or cylindrical, shell-like lithographic-printing surfaces, the combination of a primary printing-surface adapted to print a design; a curved or cylindrical, shell-like, lithographic secondary surface adapted and arranged to receive an impression by contact and to be developed into a printing-surface; a permanent conveying-surface arranged and adapted to effaceably receive an impression from the primary surface and to impart it to the secondary surface; preëstablished guides with reference to which the primary and secondary surfaces may be arranged in a precise predetermined coöperating relation both longitudinally and transversely with respect to the conveying-surface, whereby the design of the primary surface may be imparted to the secondary surface in a precise predetermined position.

6. In a machine designed to be used in making curved or cylindrical printing-surfaces, the combination of a primary printing-surface adapted to print a design; a curved or cylindrical removable and replaceable secondary surface adapted and arranged to receive an impression by contact and to be developed into a printing-surface; a rotary support having an accurate preëstablished seat so that the secondary surface and successive secondary surfaces may be mounted thereon in the same accurate predetermined position both longitudinally and transversely; a permanent conveying-surface arranged and adapted to effaceably receive an impression from the primary surface and to impart it to the secondary surface; preëstablished guides with reference to which the primary and secondary surfaces may be arranged in a precise predetermined coöperating relation both longitudinally and transversely with respect to the conveying-surface, whereby the design of the

primary surface may be imparted to the secondary surface in a precise predetermined position.

7. In a machine designed to be used in making curved or cylindrical printing-surfaces, the combination of a removable and replaceable primary printing-surface adapted to print a design; a support having an accurate pre-established seat so that the primary surface and successive primary surfaces may be mounted thereon in the same accurate predetermined position both longitudinally and transversely; a curved or cylindrical removable and replaceable secondary surface adapted and arranged to receive an impression by contact and to be developed into a printing-surface; a rotary support having an accurate pre-established seat so that the secondary surface and successive secondary surfaces may be mounted thereon in the same accurate predetermined position both longitudinally and transversely; a permanent conveying-surface arranged and adapted to effaceably receive an impression from the primary surface and to impart it to the secondary surface; pre-established guides with reference to which the primary and secondary surfaces may be arranged in a precise predetermined coöperating relation both longitudinally and transversely with respect to the conveying-surface, whereby the design of the primary surface may be imparted to the secondary surface in a precise predetermined position.

8. The combination of a series of removable and replaceable primary printing-surfaces having registering designs; a series of removable and replaceable secondary surfaces; a machine having a support for the primary surfaces and a support for the secondary surfaces, each support having a pre-established seat in which the surfaces therefor may be seated in accurate predetermined position both longitudinally and transversely, a permanent conveying-surface arranged and adapted to effaceably receive an impression from a primary surface and impart it to a secondary surface; pre-established guides with reference to which the primary and secondary surfaces may be arranged in accurate predetermined coöperating relation with respect to the conveying-surface, and means for operating the conveying-surface with a primary surface and then with a secondary surface, whereby the design of the successive primary surfaces may be carried over by the conveying-surface and imparted to the secondary surfaces in accurate predetermined position thereon and with reference to register.

9. The combination of a series of removable and replaceable primary printing-surfaces having registering designs; a series of removable and replaceable curved or cylindrical shell-like secondary surfaces; a machine having a support for the primary surfaces and a support for the secondary surfaces, each support having a pre-established seat in which the surfaces therefor may be seated in accu-

rate predetermined position both longitudinally and transversely; a permanent conveying-surface arranged and adapted to effaceably receive an impression from a primary surface and impart it to a secondary surface; pre-established guides with reference to which the primary and secondary surfaces may be arranged in accurate predetermined coöperating relation with respect to the conveying-surface, and means for operating the conveying-surface with a primary surface and then with a secondary surface, whereby the design of the successive primary surfaces may be carried over by the conveying-surface and imparted to the secondary surfaces in accurate predetermined position thereon and with reference to register.

10. In a machine designed to be used in making printing-surfaces, the combination of a primary surface, a secondary surface, and a permanent conveying-surface adapted and arranged to effaceably receive an impression from said primary surface and impart it to said secondary surface, said primary surface and said secondary surface being removable so that other primary surfaces and other secondary surfaces may be substituted therefor and work in the same place in the machine, and said primary and secondary surfaces being supported in the machine in the same or equivalent definite and predetermined coöperating relation with respect to the conveying-surface and with reference to register in the subsequent printing, whereby accuracy of register may be attained in the operation of making the secondary printing-surfaces.

11. In a machine designed to be used in making printing-surfaces, the combination of a primary surface, a curved or cylindrical lithographic secondary surface, and a permanent conveying-surface adapted and arranged to effaceably receive an impression from said primary surface and impart it to said secondary surface, and said primary and secondary surfaces being supported in the machine in the same or equivalent definite and predetermined coöperating relation with respect to the conveying-surface and with reference to register in the subsequent printing, whereby accuracy of register may be attained in the operation of making the secondary surfaces.

12. In a machine designed to be used in making printing-surfaces, the combination of a curved or cylindrical primary surface, a curved or cylindrical secondary surface, and a permanent conveying-surface adapted and arranged to effaceably receive an impression from said primary surface and impart it to said secondary surface, said primary surface and said secondary surfaces being removable so that other primary surfaces and other secondary surfaces may be substituted therefor and work in the same place in the machine, and said primary and secondary surfaces being supported in the machine in the same or equivalent definite and predetermined coöperating relation with respect to the convey-

ing-surface and with reference to register in the subsequent printing, whereby accuracy of register may be attained in the operation of making the secondary printing-surfaces.

5 13. In a machine designed to be used in making printing-surfaces, the combination of a primary surface, a secondary surface carried on a support and removable therefrom so that successive identical and interchangeable secondary surfaces may be substituted therefor and work in the same place in the machine, a permanent conveying-surface carried on a support and adapted to effaceably receive and impart an impression and means 10 for bringing the primary surface and the conveying-surface into positive contact and the successive secondary surfaces and said conveying-surface into positive contact, whereby the conveying-surface may receive impressions 15 from the primary surface and thereafter impart them to the successive secondary surfaces, the primary surface and each successive secondary surface being supported in the same or equivalent definite and predetermined coöperating relation with respect to their coacting conveying-surface, whereby from a primary surface a plurality of identical and interchangeable secondary printing-surfaces may be made having identical 20 impressions identically placed thereon.

14. In a machine designed to be used in making printing-surfaces, the combination of a primary surface carried on a support and removable therefrom so that other primary surfaces may be substituted therefor and work in the same place in the machine, a secondary surface carried on a support and removable therefrom so that successive identical and interchangeable secondary surfaces 25 may be substituted therefor and work in the same place in a machine, a permanent conveying-surface carried on a support and adapted to effaceably receive and impart an impression; and means for bringing the successive primary surfaces and the conveying-surface into positive contact and the successive secondary surfaces and said conveying-surface into positive contact, whereby the conveying-surface may receive impressions 30 from the successive primary surfaces and thereafter impart them to the successive secondary surfaces, the successive primary surfaces and the successive secondary surfaces being supported in the same or equivalent definite and predetermined coöperating relation with respect to their coacting conveying-surface and with reference to register in the subsequent printing, whereby from a series of registering 35 curved or cylindrical primary surfaces a plurality of series of curved or cylindrical registering secondary printing-surfaces may be made, the members of each series of secondary printing-surfaces being identical and interchangeable with the corresponding members of the other series of such secondary printing-surfaces.

50 16. In a machine designed to be used in making printing-surfaces, the combination of a primary surface, a secondary surface carried on a support and removable therefrom so that successive identical and interchangeable secondary surfaces may be substituted therefor and work in the same place in the machine, a permanent conveying-surface carried on a support and adapted to effaceably receive and impart an impression; and means for bringing the primary surface and the conveying-surface into positive contact and the successive secondary surfaces and said conveying-surface into positive contact, whereby the conveying-surface may receive impressions 55 from the primary surface and thereafter impart them to the successive secondary surfaces, the primary surface and the successive secondary surface being supported in the same or equivalent definite and predetermined coöperating relation with respect to their coacting conveying-surface and with reference to register in the subsequent printing, whereby from a series of registering primary surfaces a plurality of 60 series of registering secondary printing-surfaces may be made, the members of each series of secondary printing-surfaces being identical and interchangeable with the corresponding members of the other series of such secondary printing-surfaces.

65 15. In a machine designed to be used in making printing-surfaces, the combination of

a curved or cylindrical primary surface carried on a support and removable therefrom so that other primary surfaces may be substituted therefor and work in the same place in the machine, a curved or cylindrical secondary surface carried on a support and removable therefrom so that successive identical and interchangeable secondary surfaces may be substituted therefor and work in the same place in the machine, a permanent curved or cylindrical conveying-surface carried on a support and adapted to effaceably receive and impart an impression; and means for bringing the successive primary surfaces and the conveying-surface into positive rolling contact, and the successive secondary surfaces and said conveying-surface into positive rolling contact, whereby the conveying-surface 75 may receive impressions from the successive primary surfaces and thereafter impart them to the successive secondary surfaces, the successive primary surfaces and the successive secondary surfaces being supported in the same or equivalent definite and predetermined coöperating relation with respect to their coacting conveying-surfaces and with reference to register in the subsequent printing, whereby from a series of registering 80 curved or cylindrical primary surfaces a plurality of series of curved or cylindrical registering secondary printing-surfaces may be made, the members of each series of secondary printing-surfaces being identical and interchangeable with the corresponding members of the other series of such secondary printing-surfaces.

85 17. In a machine designed to be used in making printing-surfaces, the combination of a primary surface, a secondary surface carried on a support and removable therefrom so that successive identical and interchangeable secondary surfaces may be substituted therefor and work in the same place in the machine, a permanent conveying-surface carried on a support and adapted to effaceably receive and impart an impression; and means for bringing the primary surface and the conveying-surface into positive contact and the successive secondary surfaces and said conveying-surface into positive contact, whereby the conveying-surface may receive impressions 90 from the primary surface and thereafter impart them to the successive secondary surfaces, the primary surface and the successive secondary surface being supported in the same or equivalent definite and predetermined coöperating relation with respect to their coacting conveying-surface, devices for inking the primary surface, whereby from a primary surface a plurality of identical and interchangeable secondary printing-surfaces may be made having identical impressions 95 identically placed thereon.

130 18. In a machine designed to be used in making printing-surfaces, the combination of a primary surface carried on a support and removable therefrom so that other primary

surfaces may be substituted therefor and work in the same place in the machine, a secondary surface carried on a support and removable therefrom so that successive identical and interchangeable secondary surfaces 5 may be substituted therefor and work in the same place in the machine, a permanent conveying-surface carried on a support and adapted to effaceably receive and impart an 10 impression; and means for bringing the successive primary surfaces and the conveying-surface into positive contact and the successive secondary surfaces and said conveying-surface into positive contact, whereby 15 the conveying-surface may receive impressions from the successive primary surfaces and thereafter impart them to the successive secondary surfaces, the successive primary surfaces and the successive secondary surfaces 20 being supported in the same or equivalent definite and predetermined coöperating relation with respect to their coacting conveying-surface and with reference to register in the subsequent printing, and devices for inking 25 the primary surfaces, whereby from a series of registering primary surfaces a plurality of series of registering secondary printing-surfaces may be made, the members of each series of secondary printing-surfaces 30 being identical and interchangeable with the corresponding members of the other series of such secondary printing-surfaces.

18. In a machine designed to be used in making printing-surfaces, the combination of 35 a curved or cylindrical primary surface carried on a support and removable therefrom so that other primary surfaces may be substituted therefor and work in the same place in the machine, a curved or cylindrical secondary surface carried on a support and removable therefrom so that successive identical and interchangeable secondary surfaces 40 may be substituted therefor and work in the same place in the machine, a permanent curved or cylindrical conveying-surface carried on a support and adapted to effaceably receive and impart an 45 impression; and means for bringing the successive primary surfaces and the conveying-surface into positive rolling contact, and the successive secondary surfaces 50 and said conveying-surface into positive rolling contact, whereby the conveying-surface may receive impressions from the successive primary surfaces and be thereafter turned over upon the successive secondary surfaces; the successive primary surfaces and the successive secondary surfaces 55 being supported in the same or equivalent definite and predetermined coöperating relation with respect to their coacting conveying-surface and with reference to register in the subsequent printing, whereby from a series of registering curved or cylindrical primary surfaces a plurality of series of curved or cylindrical registering secondary printing-surfaces 60 may be made, the members of each series of secondary printing-surfaces being

identical and interchangeable with the corresponding members of the other series of such secondary printing-surfaces.

19. In a machine designed to be used in making a printing-surface, the combination of a secondary surface and a permanent conveying-surface comprising a unitary surface having a plurality of designs or impressions effaceably printed thereon in accurate and predetermined relation with respect to each other and with reference to register in the subsequent printing of said designs, preëstablished guides with reference to which said secondary surface and said conveying-surface 70 may be supported in the machine in predetermined coöperating relation with respect to each other, and means for bringing the conveying-surface and the secondary surface into positive contact whereby the impressions or designs of the conveying-surface are imparted to the secondary surface and said secondary surface may be made into a secondary printing-surface suitable for printing.

20. In a machine designed to be used in making a printing-surface, the combination of a secondary surface, and a permanent curved conveying-surface comprising a unitary surface having a plurality of designs or impressions effaceably printed thereon in accurate and predetermined relation with respect to each other and with reference to register in the subsequent printing of said designs, preëstablished guides with reference to which said secondary surface and said conveying-surface 90 may be supported in the machine in predetermined coöperating relation with respect to each other and with reference to register in the subsequent printing of said designs, preëstablished guides with reference to which said secondary surface and said conveying-surface may be supported in the machine in predetermined coöperating relation with respect to each other, and means for bringing the conveying-surface and the secondary surface into positive rolling contact, whereby the impressions or designs of the conveying-surface are imparted to the secondary surface, and said secondary surface 100 may be made into a secondary printing-surface suitable for printing.

21. In a machine designed to be used in making a printing-surface, the combination of a curved or cylindrical secondary surface, and a permanent conveying-surface comprising a unitary surface having a plurality of designs or impressions effaceably printed thereon in accurate and predetermined relation with respect to each other and with reference to register in the subsequent printing 115 of said designs, preëstablished guides with reference to which said secondary surface and said conveying-surface may be supported in the machine in predetermined coöperating relation with respect to each other, and means for bringing the conveying-surface and the secondary surface into positive rolling contact whereby the impressions or designs of the conveying-surface are imparted to the secondary surface and said secondary surface 120 may be made into a secondary printing-surface suitable for printing.

22. In a machine designed to be used in making a printing-surface, the combination

of a curved or cylindrical secondary surface and a permanent conveying-surface comprising a unitary surface having a plurality of designs or impressions effaceably printed thereon in accurate and predetermined relation with respect to each other and with reference to register in the subsequent printing of said designs, preëstablished guides with reference to which said secondary surface and 5 said conveying-surface may be supported in the machine in predetermined coöperating relation with respect to each other, means for bringing the conveying-surface and the secondary surface into positive contact, whereby 10 by the impressions or designs of the conveying-surface are imparted to the secondary surface and said secondary surface may be made into a secondary printing-surface suitable for printing.

20 23. In a machine designed to be used in making a printing-surface, the combination of a lithographic secondary surface and a permanent conveying-surface comprising a unitary surface having a plurality of designs 25 or impressions effaceably printed thereon in accurate and predetermined relation with respect to each other and with reference to register in the subsequent printing of said designs, said preëstablished guides with reference to which secondary surface and said conveying-surface may be supported in the machine in predetermined coöperating relation with respect to each other, means for bringing the conveying-surface and the secondary 30 surface into positive rolling contact whereby the impressions or designs of the conveying-surface are imparted to the secondary surface and said secondary surface may be made into a secondary printing-surface.

40 24. In a machine designed to be used in making a printing-surface, the combination of a curved or cylindrical lithographic secondary surface, and a permanent conveying-surface comprising a unitary surface having a plurality of designs or impressions effaceably printed thereon in accurate and predetermined relation with respect to each other and with reference to register in the subsequent 45 printing of said designs, preëstablished guides with reference to which said secondary surface and said conveying-surface may be supported in the machine in predetermined coöperating relation with respect to each other, means for bringing the conveying-surface and the secondary surface into positive rolling contact, whereby the impressions or designs of the conveying-surface are imparted to the secondary surface and said secondary 50 surface may be made into a secondary printing-surface suitable for printing.

55 25. In a machine designed to be used in making printing-surfaces, the combination of a primary printing-surface adapted to print a design; a secondary surface adapted and arranged to receive an impression by contact and to be developed into a printing-surface;

a permanent conveying-surface comprising a rubber blanket arranged and adapted to effaceably receive an impression from the primary surface and to impart it to the secondary surface; preëstablished guides with reference to which the primary and secondary surfaces may be arranged in a precise predetermined coöperating relation both longitudinally and transversely with respect to the conveying-surface, whereby the design of the primary surface may be imparted to the secondary surface in a precise predetermined position.

26. The combination of a series of removable and replaceable primary printing-surfaces having registering designs; a series of removable and replaceable secondary surfaces; a machine having a support for the primary 85 surfaces and a support for the secondary surfaces, each support having a preëstablished seat in which the surfaces therefor may be seated in accurate predetermined position both longitudinally and transversely, a permanent conveying-surface comprising a rubber blanket arranged and adapted to effaceably receive an impression from a primary surface and impart it to a secondary surface; preëstablished guides with reference to which 90 the primary and secondary surfaces may be arranged in accurate predetermined coöperating relation with respect to the conveying-surface, and means for operating the conveying-surface with a primary surface and then 95 with a secondary surface, whereby the design of the successive primary surfaces may be carried over by the conveying-surface and imparted to the secondary surfaces in accurate predetermined position thereon and with reference to register.

27. In a machine designed to be used in making a printing-surface, the combination of a secondary surface and a permanent conveying-surface comprising a unitary surface 110 consisting of a rubber blanket having a plurality of designs or impressions effaceably printed thereon in accurate and predetermined relation with respect to each other and with reference to register in the subsequent 115 printing of said designs, preëstablished guides with reference to which said secondary surface and said conveying-surface may be supported in the machine in predetermined coöperating relation with respect to each 120 other, and means for bringing the conveying-surface and the secondary surface into positive contact whereby the impressions or designs of the conveying-surface are imparted to the secondary surface and said secondary 125 surface may be made into a secondary surface suitable for printing.

28. In a machine adapted for use in making printing-surfaces, the combination of the cylinder 18, cylinder 2 and cylinder 11, and 130 means for moving the cylinders 2 and 11 to and from the cylinder 18.

29. In a machine adapted for use in making printing-surfaces, the combination of a cylin-

der adapted to support a removable cylindrical printing-surface and arranged to be moved back and forth horizontally in ways formed in the frame of the machine, an extension 5 of the way on one side of the machine being removable whereby the printing-surface may be slipped from its supporting-cylinder.

30. In a machine adapted for use in making printing-surfaces, the combination of the cylinders 2 and 18, the cylinder 2 being movable to and from the cylinder 18 and mechanism for driving said cylinders separately and together as desired.

31. In a machine adapted for use in making printing-surfaces, the combination of the cylinders 2, 18 and 11, the cylinders 2 and 11 being movable to and from the cylinder 18, and mechanism for driving the cylinder 2 separately and the cylinder 18 in conjunction with 20 either the cylinder 2 or the cylinder 11 as desired.

32. The combination of the shaft 64 having clutch 71, gears 66 and 69, two shafts as 84, having gears such as 83 and 85, cylinders 2 25 and 11 having gears as 86, and cylinder 18 having gear 35, the cylinders 2 and 11 having gears 36 and 89.

33. In a machine for use in making printing-surfaces, the combination of a primary surface; a secondary surface; and a conveying-surface; mechanism for moving the primary and secondary surfaces into and out of contact with the conveying-surface; and mechanism for driving the primary surface and conveying-surface together in operating contact and for driving the secondary surface and the conveying-surface together in operating contact, and pre-established guides with reference to which said surfaces may be brought into 40 accurate predetermined co-operating relation both longitudinally and transversely.

34. In a machine for use in making printing-surfaces, the combination of a rotary primary surface; a secondary surface; and a conveying-surface; mechanism for moving the primary and secondary surfaces into and out of contact with the conveying-surface; and mechanism for driving the primary surface and conveying-surface together in operating 45 contact and for driving the secondary surface and the conveying-surface together in operating contact.

35. In a machine for use in making printing-surfaces, the combination of a primary surface; a rotary secondary surface; and a conveying-surface; mechanism for moving the primary and secondary surfaces into and out of contact with the conveying-surface; and mechanism for driving the primary surface 55 and conveying-surface together in operating contact and for driving the secondary surface and the conveying-surface together in operating contact, and pre-established guides with reference to which said surfaces may be brought into accurate predetermined co-operating relation both longitudinally and transversely.

36. In a machine for use in making printing-surfaces, the combination of a primary surface; a secondary surface; and a rotary conveying-surface; mechanism for moving the primary and secondary surfaces into and out of contact with the conveying-surface; and mechanism for driving the primary surface and conveying-surface together in operating 70 contact and for driving the secondary surface and the conveying-surface together in operating contact, and pre-established guides with reference to which said surfaces may be brought into accurate predetermined co-operating relation both longitudinally and transversely.

37. In a machine for use in making printing-surfaces, the combination of a rotary primary surface; a rotary secondary surface; and a conveying-surface; mechanism for moving the primary and secondary surfaces into and out of contact with the conveying-surface; and mechanism for driving the primary surface and conveying-surface together in 85 operating contact and for driving the secondary surface and the conveying-surface together in operating contact.

38. In a machine for use in making printing-surfaces, the combination of a rotary primary surface; a secondary surface; and a rotary conveying-surface; mechanism for moving the primary and secondary surfaces into and out of contact with the conveying-surface; and mechanism for driving the primary surface and conveying-surface together in operating contact and for driving the secondary surface and the conveying-surface together in operating contact.

39. In a machine for use in making printing-surfaces, the combination of a primary surface; a rotary secondary surface; and a rotary conveying-surface; mechanism for moving the primary and secondary surfaces into and out of contact with the conveying-surface; and mechanism for driving the primary surface and conveying-surface together in operating contact and for driving the secondary surface and the conveying-surface together in operating contact, and pre-established guides with reference to which said surfaces may be brought into accurate predetermined co-operating relation both longitudinally and transversely.

40. In a machine for use in making printing-surfaces, the combination of a primary surface; a secondary surface; and a conveying-surface; devices for inking the primary surface; mechanism for moving the primary and secondary surfaces into and out of contact with the conveying-surface; and mechanism for driving the primary surface and conveying-surface together in operating contact and for driving the secondary surface and the conveying-surface together in operating contact, and pre-established guides with reference to which said surfaces may be brought into accurate predetermined co-operating relation both longitudinally and transversely.

41. In a machine for use in making printing-surfaces, the combination of a rotary primary surface; a rotary secondary surface; and a rotary conveying-surface; mechanism for moving the primary and secondary surfaces into and out of contact with the conveying-surface; and mechanism for driving the primary surface and conveying-surface together in operating contact and for driving the secondary surface and the conveying-surface together in operating contact.
42. In a machine for use in making printing-surfaces, the combination of a rotary primary surface; a secondary surface; and a conveying-surface; devices for inking the primary surface; mechanism for moving the primary and secondary surfaces into and out of contact with the conveying-surface; and mechanism for driving the primary surface and conveying-surface together in operating contact and for driving the secondary surface and the conveying-surface together in operating contact.
43. In a machine for use in making printing-surfaces, the combination of a primary surface; a rotary secondary surface; and a conveying-surface; devices for inking the primary surface; mechanism for moving the primary and secondary surfaces into and out of contact with the conveying-surface; and mechanism for driving the primary surface and conveying-surface together in operating contact and for driving the secondary surface and the conveying-surface together in operating contact, and preestablished guides with reference to which said surfaces may be brought into accurate predetermined coöperating relation both longitudinally and transversely.
44. In a machine for use in making printing-surfaces, the combination of a rotary primary surface; a secondary surface; and a rotary conveying-surface; devices for inking the primary surface; mechanism for moving the primary and secondary surface into and out of contact with the conveying-surface; and mechanism for driving the primary surface and conveying-surface together in operating contact and for driving the secondary

surface and the conveying-surface together in operating contact.

45. In a machine for use in making printing-surfaces, the combination of a rotary primary surface; a rotary secondary surface; and a rotary conveying-surface; devices for inking the primary surface; mechanism for moving the primary and secondary surfaces into and out of contact with the conveying-surface; and mechanism for driving the primary surface and conveying-surface together in operating contact and for driving the secondary surface and the conveying-surface together in operating contact.

46. In a machine adapted for use in making printing-surfaces, the combination of a primary surface, a secondary surface and a support carrying a permanent conveying-surface, means for bringing said surfaces into contact in pairs, and preestablished guides whereby said pairs of surfaces may be brought into accurate predetermined coöperating relation both longitudinally and transversely.

47. In a machine adapted for use in making printing-surfaces, the combination of the cylinder 18, cylinder 2 and cylinder 11, provided with intermeshing gearing and means for moving the cylinders 2 and 11 to and from the cylinder 18.

48. In a machine adapted for use in making printing-surfaces, the combination of the cylinders 2 and 18 having intermeshing gearing, the cylinder 2 being movable to and from the cylinder 18 and mechanism for driving the cylinder 2 together with and separate from the cylinder 18 as desired.

49. In a machine adapted for use in making printing-surfaces, the combination of the cylinders 2, 18 and 11, having intermeshing gearing, the cylinders 2 and 11 being movable to and from the cylinder 18, and mechanism for driving the cylinder 2 separately and the cylinder 18 in conjunction with either the cylinder 2 or the cylinder 11 as desired.
